UNITED STATES PATENT OFFICE

JOHN E. DREW, OF JERSEY CITY, NEW JERSEY, ASSIGNOR TO WADE & BUTCHER CORPORATION, A CORPORATION OF NEW JERSEY

RAZOR STROPPER

Application filed April 12, 1927. Serial No. 183,029.

This invention relates to an improved razor strop of the type used for stropping safety razor blades; and it has for its main object the production of a strop in which a blade to be stropped is moved into stropping position by a movement of an actuating handle for the device and then by a continuing movement is moved along the strop to effect the stropping operation. With this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a side elevation of a strop constructed in accordance with the invention; Fig. 2 is a sectional view on an enlarged scale of a part of the device shown in Fig. 1 and showing the manner of presentation of one side of an edge of a blade to the strop during the movement indicated by the arrow; Fig. 3 is a similar view showing the manner of presentation of the other side of an edge of a blade to the strop during the opposite movement indicated by the arrow; Fig. 4 is a plan view of the device shown in Fig. 1; and Fig. 5 is a sectional view taken on the line 5—5 in Fig. 4.

In carrying the invention into effect, there is provided a razor strop of a well known type and which may be provided with a hook at one end and a loop at the other in the usual manner, a frame mounted on said strop and adapted to be moved along said strop, a blade holder mounted in said frame and adapted to move independently of and con- currently with the frame during different parts of the stropping operation, a handle for actuating the device, and operating connections between said holder and said handle whereby movement of said handle in either direction first moves a blade into stropping position and then moves it along said strop.

These parts may be considerably varied in construction within the scope of the claims, for the specific structure selected to illus- trate the invention is but one of numerous

possible concrete embodiments of the invention. The invention, therefore, is not to be restricted to the precise details of the structure shown and described.

Referring to the drawings, 6 indicates side plates of a frame adapted to be moved along a razor strop 7 and supported thereby. There are two of these side plates and they are connected by pins 8 each of which carries a roller 9 engaging the strop 7. The rollers 9 are unsymmetrically arranged in the frame to cause the opposite sides of an edge of a curved blade to be presented to the strop 7 at the proper different angles; although this arrangement is not required in case of a flat blade. Thus the frame is mounted on the strop.

To support a blade to be stropped, there is provided a blade holder which is mounted in the frame mounted on the strop. This blade holder comprises a bar 10 carried by two levers 11—11, both of which are fulcrumed on one of the pins 8, i. e. on the pin nearest the middle of the frame including the plates 6—6.

To clamp a blade to be stropped on the bar 10, the latter is provided with two lugs 12—12 struck up from the body of the bar and projecting through apertures 13—13 in a blade B. The bar 10 is further provided with a stud 14 which passes through a central aperture in a blade and carries a clamping nut 15 of well known construction and operation.

The free ends of the levers 11—11 are connected by means of a rod 16 on which is pivotally mounted an actuating handle 17 by means of which the device is operated.

In Figs. 1 and 3 the parts are shown in the position in which they lie when the handle 17 is being moved to the left, while in Fig. 2 they are shown in the position in which they lie when the handle is being moved to the right. Assuming that the strop 7 is held taut and the parts are in the position shown in Fig. 1, and that the end of a movement to the left has about been reached. The operator then reverses the movement of the handle 17 and moves it toward the right or toward the dotted position shown. This part

of the movement to the right swings the blade from the position shown in full lines to the position shown in dotted lines, thus presenting the other side of the same edge of the blade to the strop. Continuation of the handle movement to the right moves the frame along the strop and effects the stropping action on the blade edge. At the end of the movement to the right, the position of the blade is again reversed as a movement to the left begins. The strop cannot be cut by the blade because any reverse movement of the handle at once swings the blade away from the strop, and the stropping engagement of the blade with the strop is always a trailing engagement.

What is claimed is:

1. The combination with a razor strop, of a frame movably mounted on said strop and having offset means on opposite sides of said strop arranged to form in said strop two stropping sections of different angularity with respect to the main body portion of the strop, a blade holder swingable in said frame for movement to either one of two positions in which a held blade engages said sections at different stropping angles, a handle, and connections between said handle and said holder in which the latter is fixed operating in either direction to first move the holder into one or the other of said stropping positions and then move said frame along said strop.

2. The combination with a razor strop, of a frame movably mounted on said strop and having offset means on opposite sides of said strop arranged to form in said strop two stropping sections of different angularity the latter fixed operating in either direction with respect to the main body portion of the strop, a blade holder swingable in said frame for movement to either one of two positions in which a held blade engages said sections at different stropping angles, a handle, and connections between said handle and said holder operating in either direction to first move the holder into one or the other of said stropping positions and then move said frame along said strop, said frame including two side plates spaced apart and connected by pins fixed therein supporting said offset means.

3. The combination with a razor strop, of a frame movably mounted on said strop and having offset means on opposite sides of said strop arranged to form in said strop two stropping sections of different angularity with respect to the main body portion of the strop, a blade holder swingable in said frame for movement to either one of two positions in which a held blade engages said sections at different stropping angles, a handle, and connections between said handle and said holder operating in either direction to first move the holder into one or the other of said

stropping positions and then move said frame along said strop, said frame including two side plates spaced apart and connected by two pins fixed therein below the strop and two unsymmetrically arranged pins fixed therein above the strop carrying rollers forming said offset means.

4. The combination with a razor strop, of a frame movably mounted on said strop and having offset means on opposite sides of said strop arranged to form in said strop two stropping sections of different angularity with respect to the main body portion of the strop, a blade holder swingable in said frame for movement to either one of two positions in which a held blade engages said sections at different stropping angles, a handle, and connections between said handle and said holder operating in either direction to first move the holder into one or the other of said stropping positions and then move said frame along said strop, said frame including two side plates spaced apart and connected by pins fixed therein one of which supports said connections.

5. The combination with a razor strop, of a frame movably mounted on said strop and having offset means on opposite sides of said strop arranged to form in said strop two stropping sections of different angularity with respect to the main body portion of the strop, a blade holder swingable in said frame for movement to either one of two positions in which a held blade engages said sections at different stropping angles, a handle, and connections between said handle and said holder operating in either direction to first move the holder into one or the other of said stropping positions and then move said frame along said strop, said holder including a blade supporting bar having blade positioning lugs and blade clamping means.

6. The combination with a razor strop, of a frame movably mounted on said strop and having offset means on opposite sides of said strop arranged to form in said strop two stropping sections of different angularity, a blade holder movable in said frame to cause a held blade to alternately engage said sections, a handle, and connections between said handle and said holder whereby movement of the former in either direction first moves the holder into stropping position and then moves said frame along said strop, said connections including spaced levers pivotally connected with said frame and with said handle and rigidly connected with said holder.

In testimony whereof, I have signed my name to this specification.

JOHN E. DREW. 125
